UNITED STATES PATENT OFFICE.

MINNIE C. WILBURN, OF DENVER, COLORADO.

DESIGN FOR A MEDAL.

SPECIFICATION forming part of Design No. 35,703, dated February 11, 1902.

Application filed December 9, 1901. Serial No. 85,286. Term of patent 14 years.

To all whom it may concern:

Be it known that I, MINNIE C. WILBURN, a citizen of the United States of America, residing at Denver, in the county of Arapahoe and State of Colorado, have invented and produced a certain new and original Design for Medals; and I do declare the following to be a full, clear, and exact description of the invention, such as will enable others skilled 5 in the art to which it appertains to make and use the same, reference being had to the accompanying drawings, and to the letters of reference marked thereon, which form a part of this specification.

15 My invention relates to a new and original design for a medal, of which the following is a specification, reference being had to the accompanying drawings, in which—

Figures 1 and 2 are views of the opposite 20 sides of a disk, showing my design. Fig. 3 is a section taken through the disk on the line $x x$, Fig. 1.

As shown in the drawings, the leading or 25 material feature of my design consists of a disk, upon one side, which will be termed the "front," are formed circular ribs A and B, concentrically arranged, the rib B being the smaller and the rib A being located at the outer or peripheral edge of the disk. With- 30 in the inner circle, or that inclosed by the rib B, is formed a rectangle whose sides are com- posed of ribs. Within this rectangle are formed two diagonal parallel ribs C, forming two right-angled triangles within the rect- 35 angle. In each of these triangles is formed

a heart in relief. In the segment of the circle above the rectangle is formed a figure composed of two S's crossing and so arranged that their curved extremities approach each other. In the segment of the circle below 40 the rectangle is located a similar figure. On each side of the upper figure is a fork, while horseshoes are similarly arranged on opposite sides of the lower figure. Within the space between the circles A and B are located 45 two stars. Upon the opposite or reverse side of the disk are formed four circular ribs concentrically arranged. Within each of the three spaces inclosed by the ribs are located four crosses equidistant from one another. 50 Within the inner circle are formed four intersecting isosceles triangles, forming a star-shaped figure. The bases of these triangles form a square, and at the apex of each triangle and at each corner of the square is 55 formed a figure composed of three small triangles, whose apexes are connected, two of the triangles being of equal size and smaller than the third.

Having thus described my invention, what 60 I claim, and desire to secure by Letters Patent, is—

The design for a medal as herein shown and described.

In testimony whereof I affix my signature 65 in presence of two witnesses.

MINNIE C. WILBURN.
